UNITED STATES PATENT OFFICE.

CHARLES F. HUNTOON, OF CHICAGO, ILLINOIS, ASSIGNOR TO HENRY D. LAUGHLIN,
OF CHICAGO, ILLINOIS.

BRAKE-BEAM.

960,935.

Specification of Letters Patent. Patented June 7, 1910.

Application filed December 17, 1909. Serial No. 533,709.

To all whom it may concern:

Be it known that I, CHARLES F. HUNTOON, a citizen of the United States of America, and a resident of Chicago, county of Cook, 5 State of Illinois, have invented certain new and useful Improvements in Brake-Beams, of which the following is a specification.

The main object of this invention is to provide an improved form of brake-beam 10 adapted to have great strength in proportion to the weight of the material therein, and particularly adapted to resist with minimum deflection loads such as those to which it is subjected in service and during beam 15 tests as to the limit of its strength.

Specifications for brake-beams are based 20 usually upon the amount of deflection of the beam under certain specified loads. In the usual construction of brake-beams of the 25 general type herein shown, there is a certain amount of yielding in the joints between the parts adjacent to the brake-heads. A large 30 part of the deflection of beams of usual construction is due to this yielding and in order 35 to comply with the requirements of the specifications as to deflection, it is necessary with usual constructions to make the beams much heavier than they need be to safely 40 resist the strains to which the beam is subjected in practice. The herein described invention is therefore directed to providing a 45 form of beam in which the strut may be comparatively long so as to reduce the component of load which is resisted by the tension member, and in which the joints between 50 the ends of the compression and tension members may be such as to prevent relative yielding of the parts and thereby insure 55 that the deflection resulting from a test is a true indication of the strength of the beam.

A specific construction embodying this invention and accomplishing the foregoing object is shown in the accompanying drawings, in which—

Figure 1 is a top plan of a brake-beam having adjustable brake-heads and particularly designed for high-speed service. Fig. 2 is an enlarged detail, partly sectional, 50 showing the method of connecting together the tension and compression members within the sleeve or brake-head member. Fig. 3 is a sectional detail taken on the line 3—3 of Fig. 1. Fig. 4 is an end elevation, partly in 55 section, showing a brake-head in position

upon the sleeve or brake-head member. Fig. 5 is a sectional detail of the strut, taken on the line 5—5 of Fig. 1.

In the construction shown in the drawings, the compression member 1 is of substantially U-shaped cross-section, the back or web and the top and bottom flanges being of substantially the same width. The strut 2 is of considerably greater length than is usual in brake-beams, and the tension member 3 has its middle part seated in a seat 4 at the end of the strut, and has its ends formed to lie between the top and bottom flanges of the compression member 1 and to extend substantially parallel with the compression member throughout the width of the brake-head member 5. The end parts of the tension member snugly fit between the top and bottom flanges which are at this point cut down to a width substantially the same as the thickness of the end portions 6 of the tension member, so that the combined section of the tension and compression members at this point is substantially rectangular. The ends of the tension member are 65 extended beyond the ends of the compression member, and each is enlarged to form a head 7 of substantially the same external shape as the compression member and having a shoulder 8 fitting against the end of 70 the compression member.

The head member 5 has an aperture extending longitudinally through it, and shaped to fit the adjacent parts of the tension and compression members so snugly 75 that in order to place the head member 5 in position, it is necessary to first expand the head member by heating it and then allow it to shrink after it is slipped endwise into position on the compression and tension members. The surface of the member 5 which fits against the tension member is of such form that it not only fits throughout the length of the adjacent part of the tension member, but fits particularly snugly and accurately at 9 in Fig. 2, throughout the extent of the bend in the tension member. In addition to shrinking the head member 5 in position, it is secured by means of a rivet 10 passing transversely through it and through the tension and compression members. The head member is strengthened by integral enlargements in the form of collars 11 and 12 at its ends, the collar 11 being 105 preferably the larger of the two, as it is lo- 110

cated at the point at which the head member is subjected to the greatest strain. The periphery 13 of the head member between the collars 11 and 12 is substantially a surface of revolution with respect to an axis disposed longitudinally of the compression member and is preferably cylindrical. A depression or recess 14 is formed in this surface on one side for receiving a lug 15 on the 5 brake-head 16, Fig. 4. The brake-head fits the adjacent side of the periphery 13 and has a strap 17 which extends around the opposite side of the periphery 13 and which is hinged at 18 to the head 16. A bolt 19 and 10 spring 20 draw the strap and head 16 into gripping contact with the periphery 13. This arrangement of the brake-head permits 15 it to be adjusted to different angular positions on the brake-beam, the angular movement being limited by the play of the lug 20 15 in the recess 14.

The strut 2 has one end shaped to form a strap 21 encircling the compression member and is secured in position with respect to the 25 compression member by means of a key 22. The other end of the strut is in the form of an open seat straddling the tension member. This end of the strut is prevented from shifting with respect to the tension member 30 on account of the sharp bend in the latter at this point. The seat 4 accurately fits the surface of the tension member 3 throughout the extent of the bend therein. Intermediate 35 of the ends of the strut are two apertures 23 and 24. The aperture 23 extends through the strut at an angle of about 45 degrees with respect to the plane of the beam and serves as a seat within which the brake lever is fulcrumed by means of a bolt passing 40 through the bolt hole 25. The aperture 24 extends through the strut at right angles to the plane of the beam, and serves as a seat within which is pivoted the link or other part which serves as a third suspension for 45 the brake-beam, there being two other suspensions located at the respective brake-heads and comprising parts connected to the brake-heads by means of bolts extending through the apertures 26, one of which is 50 shown in Fig. 4. There is a hole 27 in the strut for the bolt which fastens the strut to said third suspension link or part.

The points of suspension for the brake-beams are definitely located in cars constructed according to the usual standards, and brake-beams to be acceptable must conform with these standards. The gradual increase in the required strength of brake-beams on account of the usual method of attaching the third suspension part to the 55 brake-beam at the end of the strut has necessitated greatly increasing the weight of the various parts of the beams. By placing the point of third suspension at a point in the 60 strut intermediate of the tension and com-

pression members, that is, by providing the aperture 24, it has been possible with the herein described construction to arrange the metal in the beam so that less weight of material will provide greater strength.

Another important feature of the herein described construction is that the form of joints between the various members eliminates all deflection due to mere yielding of the tension member in said joints and thereby insures that the lighter beam construction will easily come within the requirements of the deflection tests.

Although but one specific embodiment of this invention is herein shown and described, 80 it will be understood that some of the details of the construction shown may be altered or omitted, within the scope of the following claims, without departing from the spirit of this invention.

I claim:

1. A brake-beam, comprising a compression member, a tension member, a strut, said tension member being bent at its ends so as to lie substantially parallel with said compression member adjacent to its ends, means for preventing relative shifting of said members in a longitudinal direction, and a brake-head member surrounding the adjacent end portions of said compression and tension members, said head member being shrunk in position so as to normally exert a pressure for forcing said members into unyielding engagement with each other.

2. A brake-beam, comprising a compression member of U-shaped cross-section, a tension member, a strut, said tension member being bent at its ends so as to lie within and substantially parallel with said compression member adjacent to its ends, means for preventing relative shifting of said members in a longitudinal direction, and a brake-head member surrounding the adjacent end portions of said compression and tension members, said head member being shrunk in position so as to normally exert a pressure for forcing said members into unyielding engagement with each other.

3. A brake-beam, comprising a compression member, a tension member, a strut, said tension member being bent at its ends so as to lie substantially parallel with said compression member adjacent to its ends, an integral shoulder on said tension member adapted to engage the end of said compression member for preventing relative shifting of said members in a longitudinal direction, and a brake-head member surrounding the adjacent end portions of said compression and tension members, said head member being shrunk in position so as to normally exert a pressure for forcing said members into unyielding engagement with each other.

4. A brake-beam, comprising a compression member, a tension member, a strut, said

tension member being bent at its ends so as to lie substantially parallel with said compression member adjacent to its ends, means for preventing relative shifting of said members in a longitudinal direction, and a brake-head member surrounding the adjacent end portions of said compression and tension members, said head member having therein an aperture shaped to fit snugly around the adjacent end portions of said compression and tension members and said head member being shrunk in position upon said tension and compression members so as to normally exert a pressure forcing them into unyielding engagement with each other, and said head member having thereon a surface bearing on said tension member and extending throughout the adjacent bend in said tension member so as to prevent yielding of the tension member at said bend when under strain.

5. A brake-beam, comprising a compression member, a tension member, a strut, said tension member being bent at its ends so as

to lie substantially parallel with said compression member adjacent to its ends, means 25 for preventing relative shifting of said members in a longitudinal direction, a brake-head member surrounding the adjacent end portions of said compression and tension members, said head member being shrunk in 30 position so as to normally exert a pressure for forcing said members into unyielding engagement with each other, the periphery of said member being substantially a surface of revolution with respect to an axis disposed 35 longitudinally of said compression member, and a brake-head mounted on said head member to have limited rotary movement with respect to said axis.

Signed at Chicago this 14th day of December 1909.
